UNITED STATES PATENT OFFICE.

JOHN R. PERKINS, OF MILFORD, NEW HAMPSHIRE.

THILL-COUPING.

SPECIFICATION forming part of Letters Patent No. 508,526, dated November 14, 1893.

Application filed February 4, 1893. Serial No. 460,969. (No model.)

To all whom it may concern:

Be it known that I, JOHN R. PERKINS, of Milford, county of Hillsborough, State of New Hampshire, have invented an Improvement 5 in Thill-Couplings, of which the following description, in connection with the accompanying drawings, is a specification, like letters on the drawings representing like parts.

My invention is embodied in a thill coupling of that class in which the lugs of the axle clip are provided with open notches to receive the thill pin which is retained seated in the said notches by a spring connected with the thill and bearing on the lugs of the 15 axle clip.

The invention relates to details of construction of the thill spring which will be hereinafter described.

Figure 1 is a side elevation of a portion of a thill and a coupling therefor, embodying this invention; Fig. 2 a front elevation of the axle member of the coupling; Fig. 3 a corresponding elevation of the thill member of the coupling detached; Fig. 4 a sectional detail on line x , Fig. 1, and Fig. 5 a detail showing the forward end of the coupling spring.

The axle member of the coupling comprises lugs or ears a between which the end b of the thill is received, the said lugs being shown in this instance as connected with the axle c by the usual clip a^2 . The said lugs a have substantially vertical open recesses or notches a^3 rounded at their lower ends to conform to the usual thill pin b^2 which projects from the sides of the end of the thill as shown in Fig. 3, so as to enter the notches a^3 when the end of the thill is between the lugs a . The outer surfaces of said lugs a are cam-shaped as shown at a^4 , said surfaces not 30 being concentric with the seat for the thill pin, but being at the greatest distance therefrom at a point diagonally below and in front of said seat and converging upward toward the front side of the recess a^3 as clearly shown 40 in Fig. 1.

In order to prevent the thill pin b^2 from rising out of the notch a^3 the thill b is provided with a stout spring d the lower end d^2 of which is wide enough to bear against the 50 outer surfaces of both lugs a and standss below the projecting ends of the thill pin b^2 as clearly shown in Figs. 1 and 3. The said thill spring d operates to hold the thill pin firmly seated in the notches a^3 , when the 55 vehicle is in use and enables the thills to be

uncoupled by turning them to substantially vertical position when the thill iron and spring come to the position shown in dotted lines Fig. 1, and the thill pin can be withdrawn vertically from the notches a^3 in the 60 usual manner. In order to secure the thill pin from endwise movement and also to facilitate the engagement of the thill member with the axle member of the coupling in the operation of coupling them together, the portion d^3 of the spring that bears against the lugs is provided with side wings or ears d^3 , properly arranged to extend upward at the sides of the lugs a , so as to stand at the ends of the thill pin b^2 , as best shown in Figs. 1 65 and 4, thereby preventing endwise movement of the latter when the coupling is engaged. The said ears d^3 , also engage the ends of the pin b^2 , when the thill is uncoupled as shown in Fig. 3, thus preventing possibility 70 of said pin becoming detached and being lost.

The spring d is shown as provided at its forward end with a spring tongue or hook d^4 extending forward under the thill which may be employed to engage with the usual safety 80 strap extending from the thill to the axle, it being necessary to disconnect such safety strap (if one is used) when the thills are uncoupled from the axle. This hook d^4 facilitates the operation of connecting and disconnecting the safety strap, as should be done whenever the thills are coupled or uncoupled.

I claim—

1. The combination of the axle clip having 90 lugs with open notches, and the thill pin to enter said notches; with the thill spring having a portion d^2 , adapted to bear on the outer surfaces of said lugs, and provided with ears d^3 , projecting across and adapted to engage 95 with the ends of the said thill pin, substantially as described.

2. The combination with a separable thill coupling comprising an axle clip with notched lugs, the thill iron and thill pin and spring, 100 of the safety strap hook d^4 , substantially as described.

In testimony whereof I have signed my name to this specification in the presence of two subscribing witnesses.

JOHN R. PERKINS.
